HEEL FOR BOOTS AND SHOES

Filed March 22, 1928

Inventor.
Edward B. Bishop
by Arthur F. Randall
atty.

UNITED STATES PATENT OFFICE

EDWARD B. BISHOP, OF HAVERHILL, MASSACHUSETTS

HEEL FOR BOOTS AND SHOES

Application filed March 22, 1928. Serial No. 263,829.

My invention relates to heels for boots and shoes and it has for its object to improve the construction thereof.

The heels of boots and shoes wear away more quickly at the rear outer sides thereof and it has heretofore been proposed to construct the heel of a boot or shoe with an adjustable block or heel-section constituting the said rear outer portion of the heel, the latter being so organized and arranged that this block could be adjusted as by reversing its position within a recess provided for it in the body of the heel, thereby to position a fresh unworn portion of said block or heel-section at this point of greatest wear.

In one heel of this class, as heretofore constructed, the adjustable heel-section was mounted in a pocket or recess immediately at the outer periphery of the heel so that its outer side constituted a portion of the outer side of the heel. The objection to this construction was that when applying a heel of this kind to a shoe the operation of trimming the heel would mis-shape the exposed side portion of the heel-section block and so change its shape that when reversed to compensate for wear it would not properly fit the cavity or recess provided for it.

In another heel of this class as heretofore provided the adjustable heel-section or block was mounted within a pocket or cavity disposed within the outline of the tread side of the heel but near the rear outer side thereof. The objection to this form of heel was that the thin wall of material between the cavity holding the adjustable heel-section and the periphery of the heel would soon break down under wear.

My invention provides a heel of the class referred to wherein the adjustable heel-section or block occupies a cavity or pocket provided upon the tread side of the heel adjacent, but inside of, the rear outer side portion of the heel so that the cavity or pocket is separated from the outer periphery of the heel by a comparatively narrow wall.

The distinguishing feature of my invention consists in incorporating within this comparatively thin marginal wall a metallic reinforcing means to strengthen and hold the same

in shape. In the best form of my invention this wall reinforcing means is part of a metallic anchoring member incorporated within the heel adjacent the inner end of the pocket or recess within which the adjustable heel-section or block is mounted and held by said anchor member.

Other features of my invention are hereinafter pointed out.

In the accompanying drawings:

Figure 1 is a side elevation, partly in section, of a portion of a shoe having a heel constructed in accordance with my invention.

Figure 2 is a bottom plan view, partly broken away, of the heel of the shoe shown in Fig. 1.

Figure 3 is a plan view of the adjustable heel-section of the heel shown in Figs. 1 and 2.

Figure 4 is a plan view of the anchor plate or member hereinafter described.

Figure 5 is an edge view of the anchor plate or member shown in Fig. 4.

Figure 6 is a detail hereinafter described.

Figure 7 is a side elevation of a portion of a boot or shoe provided with a heel embodying another form of my invention.

Figure 8 is a bottom plan view of the heel shown in Fig. 7 but with the adjustable heel-section or block removed.

Figure 9 is a detail of the anchor plate shown in Fig. 7.

In Figures 1 to 6 inclusive of the drawings I have shown my invention as embodied in a so-called rubber heel while Figures 7 and 8 illustrate the invention as embodied in a leather heel.

Having reference particularly to Figures 1 to 6, 10 represents the upper of a boot or shoe, 11 the outer sole and 12 the heel. As herein shown the heel 12 comprises a rubber top lift 13 and a leather heel seat lift 14. Upon its tread side the rubber top lift or heel 13 is made with a pocket or cavity 15 to receive within it a heel-section or block 16. The shoe shown in Figure 1 is for the right foot and as will be clear from Figure 2 the pocket 15 is positioned at the rear outer side adjacent the rear outer side of the heel and at its outer side this pocket is bounded

by a comparatively thin wall 17 whose inner and outer sides are parallel. This pocket 15 is eye-shaped, that is, it has oppositely disposed more or less pointed ends and two opposite sides which are of counterpart shape, each being formed on a differential curve and the outer side, as just pointed out, being parallel with the margin or periphery of the heel.

10 Within the pocket or cavity 15 is arranged the heel-section or block 16 which corresponds in shape with the shape of the pocket 15 having two opposite counterpart sides curved differentially to correspond with and 15 fit the opposite sides of the pocket 15.

Embedded within the heel-section or block 16 is a sheet metal reinforcing plate or core 18 formed at its middle with an aperture to receive a screw 19 by means of which said 20 plate or core is clamped fixedly to a post 20 provided upon an anchor member 21 embedded within the rubber heel lift 13 opposite and adjacent the inner end of the cavity or pocket 15.

25 The reinforcing plate or core 18 of the heel-section 16 may be provided with apertures 22, Fig. 3, through which the material of the heel section 16 extends to connect or bind together the parts thereof at opposite 30 sides of said core or plate.

So also the anchor plate 21 may be formed with apertures 23, Figure 4, through which the material of the heel lift 13 may extend to bind together the portions thereof at opposite 35 sides of said anchor plate 21.

The rubber heel lift 13 may be provided with washers 24 and holes 25 to receive the heel attaching nails 26 and the anchor plate 21 is also provided with apertures 27 for the 40 reception of other heel attaching nails 28.

An important feature of my invention consists in constructing the relatively small marginal wall 17 with metallic reinforcing and strengthening means which in Figures 1 and 45 2 is shown as a curved perpendicular flange 29 provided along the outer side of the anchor plate 21, said flange being embedded within, and at the middle of, the wall 17.

It will therefore be clear that when the 50 heel strikes down onto the ground at its rear end the strains and stresses to which the wall 17 is then subjected which tend to bend said wall away from the heel-section 16 and even to break it down, are opposed and prevented from doing so by the reinforcing flange 29.

This flange 29, as shown clearly in Figures 1 and 5, may be formed with apertures 30 through which extend bonds of rubber 60 which unite the part of the wall 17 outside of flange 29 with the part thereof that is within said flange.

The heel-section or block 16 is preferably made from rubber like the body portion of 65 the lift 13 but it may be made from any other

suitable material or combination of materials. Also, while I prefer to shape the pocket or cavity 15 and the heel-section 16 as described other shapes may be employed so long as the block 16 is adjustable to compensate for wear of the rear portion thereof. 70

With the form of block and cavity herein shown the heel section or block 16 may be adjusted both by rotation and reversal thereof. That is to say, by removing the 75 screw 19 the heel section or block 16 may be withdrawn from the cavity or pocket 15, rotated one hundred and eighty degrees and replaced thereby positioning a fresh portion of said heel-section 16 at the back of the 80 heel, or after first removing the screw 19 the heel-section or block 16 may be removed from the pocket or cavity 15, reversed and re-stored to said pocket in either of two positions. 85

The post 20 of the anchor member 21 may, as shown in Figure 6, be a section of interiorly threaded tubing riveted, or otherwise secured, within a hole provided in member 21. 90

In Figures 7, 8 and 9 which illustrate a leather type of heel the latter is made with a relatively thick top lift 13^a formed with a hole 15^a through it that is shaped, as shown in Figure 8, and positioned the same as the 95 pocket or cavity 15 of Figure 1. To the upper side of this top lift 13^a is secured, as by nails 31, a leather lift 13^b between which and the top lift 13^a is arranged the anchor member or plate 21^a provided with a post 100 20^a positioned at the middle of the hole 15^a. Thus the two lifts 13^a and 13^b constitute a heel or heel lift structure provided upon its tread side with a cavity 15^a at the inner end of which is disposed the anchor plate 21^a. 105 Within this cavity is arranged the heel-section 16 which may be constructed like the corresponding heel-section of Figures 1 and 2 and likewise secured in position within the pocket 15^a by a screw 19 engaged with the post 20^a. 110

In this form of my invention the anchor plate 21^a is provided at its outer margin with perpendicular spike extensions 29^a that are driven into the relatively narrow marginal wall 17^a of the top lift 13^a and these spikes 29^a serve to reinforce and strengthen said wall. If desired, the anchor plate 21 may also be provided at its outer margin with upwardly directed perpendicular spikes 32. These 115 spikes 32, with the spikes 29^a, serve as means for connecting the two lifts 13 and 13^b and particularly as means for connecting the relatively narrow wall 17^a with the complete lift 13^b. The completed heel structure may be attached to the shoe by nails 33. 120

The form of my invention illustrated in Figures 1 to 6, inclusive is of simple and efficient construction and may be produced by the usual methods employed in making rubber 125 130

heels or top lifts. When completed and upon a shoe the relatively narrow marginal wall 17 of the lift or heel 13 is strong, durable and so reinforced by the metallic flange 29 that it retains its position fitted snugly against the outer side of the heel-section 16.

In the form of my invention shown in Figures 7 to 9, inclusive, the anchor plate 21^a is effectually confined in position between the two lifts 13^a and 13^b, it serves as a connector uniting those two lifts, and through the spike connections 29^a and 32 is held against movement relatively to said two lifts. In this form of my invention the heel-section 16 is preferably made from rubber or the like.

It will be noted that regardless of the material from which the insert block 16 is made the same is, in the form of my invention shown in Figure 1, seated at its inner end upon a substantial layer of resilient rubber that is part of the body 13 and that this layer will serve as a cushion for the block 16 when the latter is made from a rigid material.

What I claim is:

- 25 1. A boot or shoe heel comprising a body member formed upon its tread side near the rear thereof with a pocket that is separated from the adjacent periphery of said body member by a relatively thin wall that is part of the latter; a heel-section mounted within said pocket and adjustable therein to compensate for wear thereof, and metallic means embedded within said relatively thin wall to reinforce the latter.
- 35 2. A boot or shoe heel comprising a body member formed upon its tread side near the rear thereof with a pocket that is separated from the adjacent periphery of said body member by a relatively thin wall that is part of the latter; a metallic anchor member adjacent the inner end of said pocket and extended into said relatively thin wall to reinforce and strengthen the latter; a heel-section mounted within said pocket and adjustable therein to compensate for wear of the same, and means separably connecting said heel-section with said anchor member to secure said heel-section in position within said pocket.
- 45 3. A boot or shoe heel comprising a body member formed upon its tread side near the rear thereof with a pocket that is separated from the adjacent periphery of said body member by a relatively thin wall that is part of the latter; a metallic anchor member disposed adjacent the inner end of said pocket made with a perpendicular extension embedded within and extending longitudinally of said relatively thin wall to reinforce and support the latter; a heel-section mounted within said pocket, and means separably connecting said heel-section to said anchor member so that it is removable for adjustment to compensate for wear thereof.
- 55 4. A boot or shoe heel comprising a body

member of rubber formed upon its tread side near the rear thereof with a pocket that is separated from the adjacent periphery of said body member by a relatively thin wall, said pocket being eye-shaped and having one side thereof bounded by said wall and paralleling the adjacent periphery of said body member; a metallic anchor plate embedded within said body member opposite the inner end of said pocket and formed with a perpendicular flange embedded within and extending throughout the length of said relatively thin wall to reinforce the latter, said plate being constructed with a post extending into said pocket at the middle of the latter; a heel-section of rubber mounted within said pocket; a metal plate embedded within said heel-section and abutting the lower end of said post, said plate being made with an aperture registering with said post, and a screw occupying said aperture and separably engaged with said post to fasten said plate in position against the lower end of the latter so as to provide for adjustment of said section in said pocket to compensate for wear thereof.

Signed by me at Boston, county of Suffolk and State of Massachusetts, this 16th day of March, 1928.

EDWARD B. BISHOP.
